UNITED STATES PATENT OFFICE.

WILLIAM SPENCE, OF KINGSTON, MASSACHUSETTS, ASSIGNOR OF ONE-HALF
TO FRED BRADFORD MAGLATHLIN, OF SAME PLACE.

MUSICAL INSTRUMENT.

SPECIFICATION forming part of Letters Patent No. 666,710, dated January 29, 1901.

Application filed April 16, 1900. Serial No. 13,027. (No model.)

To all whom it may concern:

Be it known that I, WILLIAM SPENCE, of 5
Kingston, in the county of Plymouth and State
of Massachusetts, have invented certain new
and useful Improvements in Musical Instruments,
of which the following is a specification.

My invention relates to stringed musical instruments, and aims to provide one which can 10
be played automatically by a current of air
or manually by a person sufficiently skilled
in its use.

A preferred form of embodiment of the invention is illustrated in the accompanying 15
drawings, wherein I have shown in Figure 1
a top view of my instrument; in Fig. 2, a side
view, partly broken away; in Fig. 3, an end
view, looked at from the right-hand side of
Fig. 1; in Figs. 4 and 5, end and side views
20 of one form of capo tasto; and in Figs. 6 and
7, side and end views of another form of capo
tasto.

In the drawings, the reference-letter A designates the body of the instrument 25
constructed in the form of an oblong box, with
a circular opening b therein, and of any suitable
resonant material.

c designates the strings or wires, which are
chorded—that is, tuned in harmony—and are
30 also so graded (gradually lessened in size
throughout the series from side to side) that
a manually-operated capo tasto, hereinafter
to be explained, may touch all the wires at
the same time.

35 d designates one form of capo tasto consisting of a piece of wood of suitable length
to extend across the wires and provided on its
under side with a strip of rubber d' or other
suitable material about one-eighth of an inch
40 or a little more in thickness.

e designates a form of capo tasto (see Fig.
6) having one or more steps e' on the upper
surface for the purpose of holding a window
at different heights, and it is provided with
45 a thin strip of rubber e'' on its under side.
This device is separate from the instrument,
and when its base at e² rests against the
instrument, as indicated in Figs. 2 and 6, the
strip of rubber will press the strings against
50 the frets. The capo tasto may be used on
the instrument to change the chords when the

instrument is used as an accompaniment in
singing, and also to change the chords when
it is played automatically by the action of
the wind, as hereinafter explained. It is also 55
to be used as a window-support, in which
case the window presses the strings down and
holds them where required.

The reference-letter f designates a device
designed either as a window-support, when 60
the instrument is placed in an open window
to be played automatically or as the support
for the arm of a player. This device bridges
over the strings, its legs f' f'' resting on top
of the instrument and being rabbeted, as at 65
f², to take over the sides of the same. One
of said legs f' is formed with a series of ver-
tical slots f³, through which currents of air
may pass when the instrument is arranged
to be automatically played by the action of 70
the wind.

g designates a hollow turbinated metallic
disk or wheel arranged to be turned or whirled
by the wind, said disk being mounted upon
a suitable stem h, which is stepped into a 75
bearing h' in the instrument, the disk when
turned acting upon the wires through the
medium of a finger i, suspended by a flexible
connection i' from the disk.

In operation the instrument is placed so 80
that the wind may act upon the blades of the
disk and rotate the latter, causing the finger
i to successively strike the strings, first pass-
ing over them in one direction and then in
the other direction. When the disk is used, 85
the bridge f may be placed over it, with the
end piece f' to windward, so that the effect
of the wind on the wheel or disk may be con-
trolled by the position of the bridge f, it be-
ing understood that the latter can be freely 90
moved along the instrument and more or less
of the series of slots brought opposite the
wheel.

A reed-plate may be applied to or incor-
porated in the end piece f', the reeds regis- 95
tering with the slots and sounding under the
action of the wind, so as to contribute to a
harmonious effect in the operation of the in-
strument.

Having thus described my invention, what 100
I claim is—

1. A capo tasto for a stringed instrument

of the character described, the same consisting of a block of suitable material adapted to extend across the strings and faced with suitable material for contact with the strings,
5 said block being stepped on the upper surface to constitute a window-support, substantially as described.

2. A capo tasto for a stringed instrument of the character described, the same consisting of a block of suitable material adapted to extend across the strings and having a base portion to rest against the instrument and a facing of suitable material for engagement with the strings, said block being stepped on the upper surface to constitute a window-support, substantially as described.

3. In an instrument of the character described the combination with the body and strings; of a journal-bearing on the body, a

wind-wheel engaged with the bearing so as 20 to rotate in a plane parallel with that of the set of strings, said wheel occupying a position over the latter and having a yielding finger or projection to sweep over the same under rotation of the wheel, substantially as 25 described.

4. The combination with a stringed instrument of the character described, of a rotary disk or wind-wheel having an appendage to act upon the strings, and a bridge-piece 30 adapted to extend across over said wheel and having a series of slots in one end, substantially as and for the purpose described.

WILLIAM SPENCE.
